UNITED STATES PATENT OFFICE.

PAUL P. HORNI, OF NEWARK, NEW JERSEY.

DESIGN FOR AN ELECTRIC LAMP.

Application filed December 9, 1926. Serial No. 19,991. Term of patent 14 years.

To all whom it may concern:

Be it known that I, PAUL P. HORNI, a citizen of the United States, and a resident of Newark, county of Essex, State of New Jersey, have invented a new, original, and ornamental Design for Electric Lamps, of which the following is a specification, reference being had to the accompanying drawing, forming part thereof.

Figure 1 is a front elevation of an electric lamp, showing my new design;

Figure 2 is a side elevation of the same; and

Figure 3 is a top plan view.

In the three figures, conventional parts, namely the words "Traffic Police" and the supporting bracket for the lamp, are shown in dotted lines.

I claim:

The ornamental design for an electric lamp, as shown and described.

PAUL P. HORNI.
